UNITED STATES PATENT OFFICE.

WILLIAM DALTON, OF SCHENECTADY, NEW YORK.

RAIL FASTENER.

Application filed February 2, 1925. Serial No. 6,408.

To all whom it may concern:

Be it known that I, WILLIAM DALTON, a citizen of the United States, and resident of the city and county of Schenectady, State 5 of New York, have invented a certain new and useful Improvement in Rail Fasteners, of which the following is a specification.

This invention relates to means for fastening rails to ties and consists in a modification of the fastening means of my prior Patent, No. 1,512,458, dated October 21, 1924.

The basic principle and essential feature 15 of novelty of my invention, which is claimed broadly in my said patent and more specifically in a particular embodiment in the present application, resides in the provision of upstanding shoulders or abutments on or 20 secured to the tie on each side of the rail, the abutment on one side presenting a substantially vertical face to the edge of the flange, while the abutment on the other side overhangs the adjacent flange but stands at 25 a greater angle to the horizontal than the top of the flange, so that, although the rail is securely held to the tie against both lateral and vertical movement, it can be easily removed by simply tilting it on the edge 30 under the overhanging abutment as a fulcrum. The embodiment of this inventive idea, shown and described in my said patent, comprises separate retainer bars, welded or otherwise permanently secured to the 35 tie. According to the present invention, the said inventive idea is embodied in a rail chair, interposed between the rail and tie and provided with the abutments above described. Two forms of chair are shown in 40 the drawing and will be described, and obviously still other forms may be devised which embody the invention. In practice, it is usually necessary to insulate the rails from the ties, since the rails are used as conductors of the signal system, and I have devised a form of insulator which is adapted 45 for use with my improved rail fastener, and which I believe to merit patent protection. The improvement claimed is here- 50 inafter fully set forth.

In the accompanying drawing:

Figure 1 is a sectional view and Figure 2 a plan view of the present invention, taken on line 2--2 of Figure 1, and

55 Figure 3 is a view, similar to Figure 1, of a modified form.

In these views, the lower part of a rail web 1, with its flange 1^a, is shown as mounted on a metal tie 2, of inverted channel shape, but it is, of course, immaterial to this 69 invention what the shape of the tie is. In fact, my improved chair may be used with wooden ties, in which case the insulation shown and hereinafter described, is unnecessary.

To removably secure the rail to the tie, I use a chair which, in the form of Figs. 1 and 2, consists of a flat plate 3, on which the rail sits and which is rigidly secured to the tie by rivets 4 or, if preferred, by 70 welding, as indicated by the dotted lines 5. Spot welding or bolts may obviously be used, if preferred.

The abutments for the rail flange are punched up from the plate, that on one 75 side, shown at 6, being bent up so as to present a substantially vertical face 7 to the edge of the flange, while that on the other side, shown at 8, is bent to overlap the adjacent flange, but at such an angle as 80 to leave sufficient space between it and the top of the flange to permit the rail to be removed by tilting it about the flange edge under the overlapping abutment 8 until the other flange edge comes above the top of 85 the abutment 6. In other words, the angle which the overlapping portion of the abutment 8 makes with the horizontal is greater than the angle which the top of the flange 1^a makes with the horizontal. However, the 90 overlapping abutment 8 contacts (disregarding the interposed insulation) with the corner of the rail flange, so that, when the rail is in place, it is securely held from vertical movement relatively to the chair and tie, as 95 well as against lateral movements.

In the form of Fig. 3, the chair is simplified by simply turning up the ends of a plate 10, secured to the tie as by the countersunk bolts shown in dotted lines 11, or 100 by welding 12, one end 13 being bent up straight to present the vertical surface 14 to the rail flange, and the other 15 being bent up and over so as to overlap the rail flange in the same manner as the abutment 8. 105

It is to be noted that, in this case, the turned up abutments may extend for the full width of the plate 10, whereas in the form of Figs. 1 and 2, the abutments do not extend for the full width, inasmuch as they are punched up from the plate and the latter necessarily extends beyond them. If 110

desired, in either case, two or more abutments may be used on one or both sides, instead of one relatively long abutment.

In order to insulate the rail from the ties, 5 I interpose between it and the chair a pad 16 of fibre, treated canvas, or the like which, in the form of Figs. 1 and 2, is slit at its ends to provide upstanding portions 17 and 18, interposed between the flange edges and 10 the abutments 7 and 8, respectively, and to provide flat extensions 19, lying on the plate on each side of the said abutments, whereby movement of the pad transversely to the tie is prevented. In the form of Fig. 3, the pad 15 20 is simply bent up at its ends, like the plate 10 to fit between the abutments 13 and 15, and the flange edges. If desired, this pad 20 may also be wider than the plate and have tongues engaging the ends of the 20 latter to prevent movement of the pad, or it may be engaged by the heads of the bolts 11.

Minor changes in the form of the chair may be made without departing from the invention. As an alternative construction, 25 the chair itself may be made of insulating material which, in that case, must be sufficiently stiff and unyielding.

What I claim is:

1. Rail fastening means, comprising a 30 plate adapted to be rigidly secured to the tie beneath the rail, and upstanding abutments on said plate to engage the rail flange, the abutment on one side presenting a substantially vertical face to the adjacent edge 35 of said flange, and the abutment on the other side being bent to overlap the adjacent edge of said flange, said overlapping abutment standing at a greater angle to the horizontal than the top surface of said flange, whereby 40 the rail is securely held against both lateral and vertical movement but can be removed from the tie by tilting it about the flange edge which lies under said overlapping abutment.

2. A rail chair adapted to be rigidly fastened to a tie and comprising a flat portion to be interposed between the rail and tie, an upstanding flange on one side to present a substantially vertical face to the adjacent 50 flange edge, and a bent over flange on the other side to overlap the adjacent flange edge, said overlapping flange standing at a greater angle to the horizontal than the top surface of said flange, whereby the rail is securely held against both lateral and vertical movement but can be removed from the tie by tilting it about the flange edge which lies under said overlapping flange.

3. A rail chair adapted to be rigidly fastened to a tie and comprising a plate to be

interposed between the rail and tie, one edge of said plate being turned up to form a vertical abutment for one edge of the rail flange, and the opposite edge of said plate being turned up and bent to overlap the 65 other edge of said flange, said overlapping portion standing at a greater angle to the horizontal than the top surface of said flange, whereby the rail is securely held against both lateral and vertical movement 70 but can be removed from the tie by tilting it about the flange edge which lies under said overlapping portion.

4. Rail securing means, comprising a chair having a vertical abutment for one 75 rail flange edge and an overlapping abutment for the other rail flange edge, said overlapping abutment standing at a greater angle to the horizontal than the top of said flange, to permit the rail to be removed from 80 the chair by tilting it, and an insulating pad adapted to be interposed between the rail and chair and having slit portions bent up to lie between said abutments and the flange edges, flat portions being left to engage the 85 ends of said abutments to prevent movement of the pad longitudinally of the rail.

5. The combination with means to removably secure rails to metal ties, comprising a vertical abutment for one edge of the rail 90 flange and an overlapping abutment for the other edge, of an insulating pad having a flat portion adapted to underlie the rail, and slit to form tongues adapted to fit between said abutments and said flange edges 95 and other tongues adapted to engage the sides of said abutments, whereby said pad is held against movement in any direction.

6. A pad for insulating rails from metal ties which are provided with means for removably securing the rails thereto, said pad comprising a flat portion to underlie the rail with its ends slit to engage said means laterally, the portions between the slits being adapted to be bent up to fit between said 105 means and the rail flange.

7. Rail securing means, comprising a chair made of insulating material and having a vertical abutment for one edge of the rail flange, and an overlapping abutment 110 for the other edge, said overlapping abutment standing at a greater angle to the horizontal than the top of said flange, whereby the rail can be removed from the chair by tilting it about its edge beneath said overlapping abutment as a fulcrum.

In testimony whereof, I have hereunto set my hand and seal, this 28 day of January, 1925.

WILLIAM DALTON.
